TOY ANTI AIRCRAFT GUN

John De Cicco, Valley Stream, N. Y.

Application September 13, 1951, Serial No. 16,625

Term of patent 3½ years

(Cl. D34—15)

To all whom it may concern:

Be it known that I, John De Cicco, a citizen of the United States, residing at Valley Stream, in the county of Nassau and State of New York, have invented a new, original, and ornamental Design for a Toy Anti-Aircraft Gun, of which the following is a specification, reference being had to the accompanying drawing, forming part thereof.

In the drawing

Fig. 1 is a side elevational view of a toy anti-aircraft gun, showing my new design;

Fig. 2 is a top plan view thereof;

Fig. 3 is a front elevational view; and

Fig. 4 is a rear elevational view thereof.

I claim:

The ornamental design for a toy anti-aircraft gun, substantially as shown.

JOHN DE CICCO.
